UNITED STATES PATENT OFFICE.

JOHN SHELLENBERGER, OF INDIANAPOLIS, INDIANA, ASSIGNOR OF ONE-HALF TO CHARLES P. JACOBS, OF SAME PLACE.

WOODEN BOTTLE-WRAPPER.

SPECIFICATION forming part of Letters Patent No. 272,910, dated February 27, 1883.

Application filed December 26, 1882. (No model.)

To all whom it may concern:

Be it known that I, JOHN SHELLENBERGER, of Indianapolis, Indiana, have invented a new and useful Improvement in Bottle-Wrappers, 5 of which the following is a description, reference being made to the accompanying drawings, in which like letters represent like parts.

My invention belongs to that class of bottle-wrappers which are made of thin sheets of 10 wood, and is intended to provide by its peculiar form of construction for the elevating of a portion of its surface into ridges which shall form a projecting and yielding surface for keeping the wrapped bottles apart, and doing 15 away with the necessity of using compressible or elastic bands or cords for such purpose.

My invention is an improvement upon the wooden bottle-wrapper described in Letters Patent granted to me January 4, 1881, and 20 numbered 236,186.

In the drawings, Figure 1 represents a strip of wood or veneer stamped and cut, the edges untrimmed, in which there are three series of 25 ridges—one, A, extending from the top of the wrapper some distance downward; another, B, separated by a short space of unridged wood from it, and a third, C, near the bottom of the wrapper. The cross-cuts at the end of the ridges are indicated by K in each figure. The 30 side cut is indicated by K'. Fig. 2 represents a piece of wood or veneer stamped and cut, the edges untrimmed, in which there are two series of ridges separated by one unridged space of wood. Fig. 3 is a cross-section along 35 the line S S, Fig. 2, showing how the sides are cut, and the ridges formed by turning out the strip, and is on a scale of twice the size of the other figures.

My wrapper may be made on any suitable 40 machine. The strip of wood or ribbon being fed into it, so that the stamping-block, provided with sets of cutting-blades, will cut through the wood at right angles to the grain, as at K, and at the same time make the longitudinal cut K'. The cut K' and at least one 45 of the cuts K that is at one end of the ridge should be cut clear through. Indeed, I prefer to cut the cross-cuts at each end clear through the wood, as the strip which forms the ridge, 50 being thus cut free from the body-sheet of the wood at both ends and one side, leaving the other side attached to the body of the wrapper, may be readily turned out from the body

of the wrapper at any desired angle, forming a number of strips or ridges at an angle from the bottle when covered with the wrapper. These strips thus turned out have sufficient elasticity or spring to resist any ordinary concussion in shipment.

This application is not made to cover any claims allowed in my Letters Patent No. 236,186, but as an improvement, the wrapper herein described having both ends and one side of the radiating strips cut from the body of the sheet, as hereinbefore described, and 6 having spaces left in the body-sheet of the wrapper between the series of ridges.

The wrapper shown in Fig. 2 is especially adapted to be used on square bottles or small round bottles where the wrapper is not compressed around the neck of the vessel.

What I claim and desire to secure by Letters Patent is the following:

1. As an article of manufacture, a bottle-wrapper made of a thin sheet of wood in which 7 projecting ridges are formed at the upper end and in one or more places in the body of the wrapper with spaces of wood between which are not thus ridged, the wood at one or both ends of such projecting ridges being cut 8 through substantially at right angles to the line of the ridge and at one side, allowing the ridge-strips to be turned out readily to form a projecting and yielding surface, substantially as and for the purposes described. 8

2. A wooden bottle-wrapper having projecting ridges formed thereon which are cut free from the body-sheet at both ends and at one side, substantially as described.

3. A wooden bottle-wrapper having parts 9 or strips cut out of the body, so as to be free from the wrapper-sheet at both ends and on one side of the strip, leaving the other side attached to the body of the wrapper, the strips being turned out from the body of the wrapper at any desired angle to form a series of elastic and compressible ridges all round the bottle, substantially as and for the purpose described. 9

In witness whereof I have hereto set my hand, 10 at Indianapolis, Indiana, this 20th day of December, 1882.

JOHN SHELLENBERGER.
